RADIO-FREQUENCY ENERGY TRANSFER
SWITCH

Loren E. Bollinger, Columbus, Ohio, assignor, by
mesne assignments, to the United States of
America as represented by the Secretary of
the Navy

Application January 30, 1953, Serial No. 334,346

7 Claims. (Cl. 200—152)

1

This invention broadly relates to switching apparatus; more particularly, this invention relates to a switching apparatus for use with radio-frequency energy of appreciable power levels when cooling problems exist.

The primary object of the invention is to provide a novel and improved switching apparatus which is more inexpensive and of simpler construction than existing devices of a similar type.

Another object of the invention is to provide a novel radio-frequency transfer switch which is capable of handling energies of large magnitudes without undue heating of a switching apparatus.

A still further object of the invention is to provide a novel switching apparatus which is capable of selectively connecting one electrical conductor to another in a most expeditious and efficient manner.

A still further object of the invention is to provide a novel switching apparatus for use with water-cooled conductors where very high energy, radio-frequency currents are involved.

Other objects and a clear description of the invention may be obtained from the specification to follow, the claims, and the drawings wherein:

Figure 1 shows the switching unit of this invention;

Figure 2 shows a cross-sectional view of a portion of the switching apparatus shown in Figure 1; and

Figure 3 shows a plurality of switch units as shown in Figure 1 supported on a rack or base member.

Referring more particularly to Figures 1 and 2, the apparatus of the invention includes a switch housing 10 made of an insulating material, such as Lucite, having a cavity 13 therein which is closed on the top thereof by a cap 11 screwable into the threaded top portion of cavity 13. A hollow electrical conductor 14 passes through the housing 10 and the lower portion of cavity 13. A second electrical conductor 12 passes through the housing 10 and cavity 13 above electrical conductor 14 and preferably at a different angle relative thereto to avoid any interference between the conductors.

An opening 9 is located in the bottom of housing 10 to communicate with cavity 13 in order that a conducting fluid may be fed to and emptied from cavity 13. A rigid conduit section 16 passes through opening 9 and communicates with a supply bulb 32 through a flexible rubber conduit 28. Mercury is a suitable conducting fluid. In such case, a vent opening 15 is made in the top portion of cavity 13 in order that

5 mercury vapor may be returned to the mercury supply bulb 32 rather than be vented to the air which might endanger operating personnel. A rigid conduit section 18 is fixedly inserted in the vent opening 15 and is connected to a flexible rubber conduit 30 which communicates with the top portion of the mercury supply bulb 32.

10 Electrical conductors 12 and 14 are respectively made hollow so that a cooling fluid such as water may be passed through the center thereof. The walls of the conductor may be made of metal, so that they are electrically conductive. Water is circulated through the conductors by connecting suitable nonconductive flexible hoses 24 and 26 respectively to the ends of the electrical conduit 14 and nonconductive conduits 20 and 22 are respectively connected to the ends of the electrical conductor 12. Suitable electrical contact with conductors 12 and 14 may be made by similar tubing or with other suitable electrical conductors, such as 36 and 38, respectively, connected to electrical conductors 12 and 14.

15 The operation of the switch device as shown 20 may be explained as follows:

First of all, the object of the switching apparatus shown is to electrically connect conductors 12 and 14 together when it is desired that the switch be in the closed position. To effect this 25 result, the supply bulb 32 is partially filled with mercury; then the various connections to the supply bulb are made as shown in Figure 1, so that the vent opening 15 is connected to the top portion of the bulb 32, and conduit 28 connects 30 with the rigid conduit 16 in the opening 9 at the bottom of housing 10 and also to the neck or opening of the bulb 32 at the other end thereof. Mercury bulb 32 is inverted, so that the open neck portion thereof is facing downward. 35 When the mercury supply bulb 32 is lowered to a position below housing 10, then the mercury will not, of course, enter the cavity 13 of housing 10. When, however, the bulb is raised to a position such that the level of mercury 40 therein is appreciably above top conductor 12, then mercury will enter the housing 10 and will fill in the space between the conductors 12 and 14 thereby making electrical connection therebetween. The water flowing to conductors 12 and 45 14 cools the conductors, and also the mercury and surrounding portions of the switch housing 10.

50 In this example, where the housing 10 is made of Lucite and appreciable currents are involved, if power were applied to the circuit before the

mercury filled in the space between conductors 12 and 14, the resultant arc would probably melt the Lucite housing 10. Therefore, in this example, the power is actually not turned on (it is turned on by some other external means) until the mercury has filled in the space between the conductors 12 and 14 within the cavity 13. For this example, the switches are not used to turn power on and off but rather are used as a means of selectively connecting one of a plurality of components into an electrical circuit. For example, in a radio circuit, a switch such as shown in Figure 1 may be used in series with each of a plurality of inductance coils used as frequency-determining elements to selectively insert the proper coil in the associated circuit.

Where it is desired to use the switch unit shown in Figure 1 as a means of turning power on and off, the current and voltage should be limited to such a value that a destructive mercury arc will not form or a means to quench the mercury arc should be provided together with the consideration that the switch housing 10 should be made of a material which will withstand high temperature such as ceramic material known for its high heat resistance.

Reference should now be made to Figure 3 which shows a mounting apparatus for use with a plurality of switching units as shown in Figure 1. The support apparatus there shown resembles an inverted box and has a horizontal support member 44 on which the various switch housings 10a, 10b, 10c, and 10d are suitably mounted. The housing is preferably made of an insulating material to reduce the possibility of short circuits.

An efficient switch and conductor cooling system is provided by interconnecting electrical conductors 14a, 14b, 14c and 14d together by suitable conduits. Thus, conduit 47 communicates with one end of conductor 14a associated with switch housing 10a and an inlet junction member 55. Conduit 47 must be an electrical conductor, since it carries electrical power arriving at connection 53 to conductor 14a. Inlet 55 serves as a power inlet as well as a water inlet. Connection is usually made with hollow copper tubing (thus supplying power and water) from the power source to inlet 55. A rubber hose section 53 extends from the other end of conductor 14a to one end of conductor 14d of adjacent switch housing 10d. A conduit 49 extends between the other end of conductor 14d and an outlet junction member 59. Conduit 49 must be an electrical conductor for the same reasons as referred to above. Conduit 47' connects with inlet junction member 55 and one end of conductor 14b of switch housing 10b. Conduit 47' must be an electrical conductor for the same reasons as referenced above. Another rubber hose section 53' connects between the other end of conductor 14b and one end of conductor 14c of adjacent switch housing 10c. Conduit 49' connects the other end of conductor 14c to outlet junction member 59. Conduit 49' must be an electrical conductor for the same reasons as referenced above. Inlet junction member 55 is connected to a suitable source of cooling liquid under pressure and outlet junction member 59 may communicate with a drain or to the liquid source itself. Inlet junction member 55 serves as an inlet connection for water and electrical energy. Outlet junction 59 serves as an outlet connection for water and return connection for electrical energy. Water passing through the conduit sys-

tem just described cools the conductors and also the switch housing 10. Although not shown in the drawings, conduits 12a, 12b, 12c, and 12d are similarly connected.

Extending downwardly from two opposite sides of horizontal support member 44 are vertical wall members 46 and 46' which act as supporting legs for the structure. At the opposite ends of the horizontal plate member 44 are upwardly extending plate members 48 and 48', respectively, which connect with vertical side plate members 45 and 45' to form respective housings in which the mercury supply bulbs associated with each switch housing may be supported. These two mercury supply bulbs support housings each have two horizontal shelves 50, 52, 50', and 52', respectively. Each of the shelves include a suitably sized opening, such as 54-54', 56-56', 60-60', and 62-62' for each supply bulb. The level of the upper shelves 50 and 50' is such that the level of the mercury in the bulbs supported therein is above the upper space between the electrical conductors of the associated housing. This will cause mercury to fill in the space between the conductors of the associated housing to cause the switch to be in the closed position. The lower shelves 52 and 52', respectively, located at a level beneath the electrical conductors of the housings, so that when the mercury supply bulbs are supported at this level, mercury will not enter the housing at a sufficient level to connect the space between the conductors of each housing. In order to readily insert the bulbs into the openings, each opening communicated with the outer portion of the structure by means of suitable slots, such as 55, 57, 55', and 57', etc. Normally, the mercury supply bulbs are supported on the lower shelves 52-52'. When it is desired to close a particular switch, the mercury supply bulb associated with such switch is slid into the nearest opening in the upper shelf. The neck portion of the bulbs shown in the drawings are made sufficiently narrow to slide in one of the slots associated with the support openings just described.

The invention provides a very convenient and efficient switch unit for use with electrical currents of high magnitudes where a heating problem exists.

It should be understood that numerous modifications may be made of the specific and preferred embodiments of the invention without deviating from the broader and more generic aspects of the invention.

I claim:

1. A switch device comprising a hollow housing made of an insulating material, two hollow separated electrical conductors passing through the hollow portion of said housing, an opening in the bottom of the hollow portion of said housing, means communicating with said latter opening for selectively filling and emptying the portion of said hollow housing extending between said separated conductors through said opening with a highly conductive fluid whereby said conductors may be respectively electrically connected and disconnected.

2. A switch device comprising a hollow housing made of an insulating material, two hollow separated electrical conductors passing through the hollow portion of said housing, means for directing a cooling fluid into the hollow portion of said conductors whereby said conductors are cooled, an opening in the bottom of the hollow portion of

said housing, means for communicating with said latter opening for selectively filling and emptying the portion of said hollow housing extending said separated conductors through said opening with a highly conductive fluid whereby said conductors may be respectively electrically connected and disconnected.

3. A switch device comprising a housing having a cavity therein, a first hollow electrical conductor extending through the housing and passing through the bottom portion of said hollow cavity, a second hollow electrical conductor extending through the said housing and the cavity therein above said first conductor, means for passing a cooling fluid through said electrical conductors for cooling said conductors, an opening in the wall of said housing communicating with said cavity, means communicating with said latter opening for selectively filling and emptying the portion of the cavity in said housing extending between said separated conductors through said opening with a highly conductive fluid whereby said conductors may be respectively selectively electrically connected and disconnected.

4. A switch device comprising a hollow housing made of an insulating material, two hollow separated electrical conductors passing through the hollow portion of said housing, an opening in the bottom of the hollow portion of said housing, means communicating with said latter opening for selectively filling and emptying the portion of said hollow housing extending between said separated conductors through said opening with mercury whereby said conductors may be respectively selectively electrically connected and disconnected.

5. A switch device comprising a hollow housing made of an insulating material, two hollow separated electrical conductors passing through the hollow portion of said housing, means for directing a cooling fluid into the hollow portion of said conductors whereby said conductors are cooled, an opening in the bottom of the hollow portion of said housing, means for communicating with said latter opening for selectively

filling and emptying the portion of said hollow housing extending said separated conductors through said opening with mercury whereby said conductors may be respectively selectively electrically connected and disconnected.

6. A switch device comprising a housing having a cavity therein, first hollow electrical conductor extending through the housing and passing through the bottom portion of said hollow cavity, a second hollow electrical conductor extending through the said housing and the cavity therein above said first conductor, means for passing a cooling fluid through said electrical conductors for cooling said conductor, an opening in the wall of said housing communicating with said cavity therein, means for communicating with said latter opening for selectively filling and emptying the portion of said hollow housing extending conductive said separated conductors through said opening with a highly conductive fluid whereby said conductors may be respectively selectively electrically connected and disconnected.

7. A switch device comprising a housing having a cavity therein made of an insulating material, a first opening in said housing communicating with the bottom portion of the cavity, a second opening in said housing communicating with the upper portion of said cavity, a first hollow electrical conductor passing through said housing and cavity therein, a second hollow electrical conductor passing through said housing and cavity, said conductor located beneath said second opening, means for passing a cooling fluid through said hollow conductors, a source of mercury, means for selectively forcing mercury through said first opening in said housing to fill up said cavity between said conductors to electrically couple them together, conduit means coupled between said second opening and said mercury source to vent off any mercury vapor collecting above said conductors.

LOREN E. BOLLINGER.
